THROTTLE VALVE OPERATING MECHANISM

Application filed July 29, 1929. Serial No. 381,820.

This invention relates generally to throttle valve operating mechanisms, and more particularly to such mechanisms adapted normally for operation by fluid pressure, and in the emergency of failure of fluid pressure for operation by manual pressure.

An object of the present invention is to provide a throttle valve operating mechanism of the type indicated, adapted for compact application in the cab of locomotives having the throttle rod extended through the back head of the boiler.

A further object of the invention is to provide a throttle valve operating mechanism of the type indicated which has an increased factor of safety, which effects a substantial economy in space, which is economical to manufacture and maintain, and which is highly efficient in operation.

The invention claimed is hereinafter fully set forth.

In the accompanying drawings: Figure 1, is a rear view in elevation of a construction embodying the invention; Fig. 2, a top plan view of the construction shown in Fig. 1; Figs. 3, 4 and 5, are, respectively, a top plan, a rear, and, a side view, all on an enlarged scale, and partly in elevation and partly in section, of the mechanism shown in Fig. 1; Fig. 6, an isometric view of the piston element of the motor; Fig. 7, a perspective view on an enlarged scale, showing the operative connections between certain of the parts; and, Fig. 8, a view in side elevation showing the mechanism inclusive of a throttle valve.

In the practice of the invention, referring descriptively to the specific embodiment thereof which is selected for exemplification herein, the throttle valve 1, is normally operated by a fluid pressure motor 2, controlled by an auxiliary valve 3, in turn controlled by a hand lever 4.

The throttle valve is disposed in the steam dome 5, of a locomotive boiler 6, and is operatively connected to a throttle rod 7, by a stem 8 and a bell crank lever 9 journaled to a stand pipe 10. The throttle rod extends longitudinally of the boiler and passes through a stuffing box 11, attached to the back head 12, of the boiler. The rear end of

the throttle rod is pivotally connected to the horizontally disposed hand lever 4, by a pair of parallel links 14. The links 14, are connected at one end by a pivot pin 15, to a fitting 16 on the rear end of the throttle rod, and at the other end by a pivot pin 17, to the hand lever.

The fluid pressure motor comprises two axially aligned, suitably bored, spaced cylinders, 18 and 18a, and a piston element embodying two balanced pistons 19 and 19a, one fitted for reciprocation in each of the cylinders. The cylinders are formed in an integral casting, which also comprises a collar 11e for supporting the casting on the stuffing box 11; a lug 20 for supporting the casting on a bracket 21 attached to the backhead 12; the seat 22, of the auxiliary valve 3; abutments 22a and 22b for limiting the movement of an auxiliary valve control lever 22c; a lug 23a, for supporting a quadrant 23; and a pair of parallel lugs 24, for supporting the pivot pin 25, of bell crank lever 26. It is to be noted that to effect economy of space in the cab, the cylinder casting is disposed parallel with the backhead. It is further to be noted that to permit proper adjustment of the casting to the backhead, the stuffing box, 11, is formed with a spherical end 11a, which fits against a bevelled edge 12a, in the backhead, and with a flange 11c, for attaching studs 11d. Removable heads 18b are fastened to the ends of the cylinders by bolts 18c.

The piston element of the motor is also formed as an integral casting, and comprises a stem 19b which connects the pistons and embodies two parallel bars spaced apart to provide a slot 19c, adapted to receive the end of one arm 26a of bell crank lever 26, which lever has its other arm 26b pivotally connected to the hand lever 4 by the pin 17. A pivot pin 19d, spans the slot 19c in the piston stem, and has its ends fastened in bores in the bars thereof. Rotatably mounted on the pin 19d, is a block 19e, slidably fitted between the jaws 26c, of the arm 26a, of the bell crank lever. The arms 26a and 26b of the bell crank lever are transversely spaced.

by a knuckle 26d which is journaled on the pivot pin 25, fitted in the lugs 24.

The auxiliary valve 3 for controlling the movements of the piston element to effect the desired adjustments of the throttle valve, comprises the seat 22, a removable casing element 22d, a disc valve 22t, a stem 22f, for oscillating the disc valve, a follower 22g, and a spring 22h, interposed between the follower and an end of the casing element, and adapted to press the disc valve snugly against the seat 22. The control lever 22c, which serves to oscillate the disc valve, has one of its ends rigidly connected to the valve stem 22f, and its other end disposed for movement between the abutments 22a and 22b. The free end of the lever arm is pivotally connected to one end of a pair of parallel links 22j, by a pin 22k, which links have their other 20 end pivoted to the hand lever 4 by a pivot pin 22m.

The seat 22 of the auxiliary valve is formed with three ports 22n, 22p, and 22q, the port 22p, being disposed intermediate the others 25 and exhausting to the atmosphere, and the ports 22n and 22q communicating with conduits 22r and 22s, respectively, which lead, respectively, into the outer ends of the cylinders 18 and 18a. The valve disc is provided with a central channel or recess, adapted, upon selective movements of the disc, to permit exhaust of pressure fluid from one or the other of the ports 22n or 22q, and through the port 22p to the atmosphere. By referring 30 to the drawings, it will be obvious that the valve disc is adapted to be moved to a central or neutral position where equilibrium of pressures on the pistons will be established and movement of the piston element arrested, with consequent maintenance of the throttle valve in any particular position of adjustment selected; to a throttle valve opening position, where pressure will be exhausted from the cylinder 18 and additional pressure 35 admitted to cylinder 18a, to effect the desired degree of opening of the throttle valve; and to a throttle valve closing position, where pressure will be exhausted from the cylinder 18a and additional pressure admitted to cylinder 18, to effect the desired degree of closure of the throttle valve.

The operation of the mechanism is as follows: assuming that the parts are in total throttle valve closure position, and that proper fluid pressure is present for operating the motor, when the hand lever 4 is pulled outwardly, it will fulcrum on the pin 17, and through the links 22j push the control lever 22c, so as to oscillate the disc valve 22t to a 55 position where fluid pressure will be exhausted to the atmosphere from the cylinder 18 and admitted from a source of supply to cylinder 18a. The piston element will then be set in motion and through the bell crank lever 26 and throttle rod 7, will pull the

throttle valve open. When substantially the desired opening of the throttle valve has been effected, the hand lever is latched to the quadrant 23, whereupon the slight continued movement of the piston element will act to move the auxiliary valve disc to neutral, where the pressures acting on the pistons will be balanced, and the throttle valve held positively in the desired adjustment. The various closing adjustments of the throttle valve 70 are effected in a substantially similar manner by reversing the movement of the hand lever. 75

In the emergency of failure of fluid pressure, the control lever 22c will move into contact with either the abutment 22a or the abutment 22b, upon movement of the hand lever, whereupon the hand lever will fulcrum upon the pivot pin 22m, to effect the desired adjustments of the throttle valve. 80

It will be noted that by employing a construction wherein the piston element reciprocates in a path transverse to the path of reciprocation of the throttle rod, a substantial economy of space in the cab is effected. 85

While one of the preferred forms of construction has been described and shown, it is obvious that many variations in procedure, form, arrangement, and construction may be resorted to, and the invention, therefore, is not limited to the particular embodiment disclosed, but includes such changes and modification as come within the spirit and scope 90 of the invention as set forth in the appended claims. 95

The invention claimed and desired to be 100 secured by Letters Patent is:

1. In a throttle valve operating mechanism, the combination of a reciprocable throttle rod; a fluid pressure motor embodying a piston element reciprocable in a path transverse to the rod; an auxiliary valve for controlling the application of fluid pressures to the piston element; and means connected to the piston element, the auxiliary valve, and the rod, adapted to control the operation of the auxiliary valve, and to translate reciprocal movements of the piston element to reciprocal movements of the rod, said means including a hand lever, a control lever connected to the valve, a link pivotally connected to the control lever and the hand lever, and a bell crank lever having one arm pivotally connected to the piston element and another arm pivotally connected to the rod. 110

2. In a throttle valve operating mechanism, the combination of a reciprocable throttle rod; a fluid pressure motor embodying a piston element reciprocable in a path transverse to the rod; an auxiliary valve for controlling the application of fluid pressures to the piston element; and means connected to the piston element, the auxiliary valve, and the rod, adapted to control the operation of the auxiliary valve, and to translate reciprocal movements of the piston element to re- 120

125

ciprocal movements of the rod, said means including a hand lever, a link pivotally connected to the rod, a control lever connected to the valve, a link pivotally connected to the control lever and the hand lever, and a bell crank lever having one arm pivotally connected to the piston element and another arm pivotally connected to the hand lever and the first mentioned link.

10 3. In a throttle valve operating mechanism, the combination of a reciprocable throttle rod; a fluid pressure motor embodying a reciprocable piston element; an auxiliary valve controlling the application of fluid
15 pressure to the piston element; a hand lever; and means operatively connecting the hand lever, the throttle rod, the motor, and the auxiliary valve, adapted to control the operation of the valve in response to movement of the
20 hand lever, and to translate reciprocal movements of the piston element to reciprocal movements of the throttle rod, said means including a bell crank lever having one arm connected to the piston element and another
25 arm connected to the hand lever, and the rod.

4. In a throttle valve operating mechanism, the combination of a reciprocable throttle rod; a fluid pressure motor embodying a reciprocable piston element; an auxiliary valve for controlling the application of fluid pressures to the piston element; a hand lever, and means operatively connecting the hand lever, the throttle rod, the piston element and the auxiliary valve, adapted to control the operation of the auxiliary valve in response to movements of the hand lever, and to translate reciprocal movements of the piston element to reciprocal movements of the throttle rod, said means including a control lever connected to the auxiliary valve, a link pivotally connected to the control lever and to the hand lever, and a bell crank lever having one arm pivotally connected to the piston element and another arm pivotally connected to the rod.

5. In a throttle valve operating mechanism, the combination of a reciprocable throttle rod; a fluid pressure motor embodying a reciprocable piston element; an auxiliary valve for controlling the application of fluid pressures to the piston elements; a hand lever; a quadrant; and means operatively connecting the hand lever, the throttle rod, the piston element, and the auxiliary valve, adapted to control the operation of the valve in response to movements of the hand lever, and to translate reciprocal movements of the piston element to reciprocal movements of the throttle rod, said means including a link pivotally connected to the throttle rod and to the hand lever, a control lever connected to the auxiliary valve, a link pivotally connected to the control lever and to the hand lever, and a bell crank lever having one arm pivotally connected to the piston

element and another arm pivotally connected to the first mentioned link.

6. In a throttle valve operating mechanism the combination of a throttle rod reciprocable in the direction of its length; a fluid pressure motor embodying two axially aligned spaced cylinders disposed in a plane perpendicular to the vertical plane of the throttle rod, and a piston element embodying two spaced pistons connected by a common stem, one of the pistons being disposed for reciprocation in each of the cylinders; a pivot pin connected to the piston stem; an auxiliary valve for controlling the application of fluid pressures to the pistons; a hand lever; and means operatively connecting the hand lever, the throttle rod, the piston element, and the auxiliary valve, adapted to control the operation of the auxiliary valve in response to movements of the hand lever, and to translate reciprocal movements of the piston element to reciprocal movements of the throttle rod, said means including a link pivotally connected to the throttle rod and the hand lever, a control lever connected to the auxiliary valve, a link pivotally connected to the control lever and the hand lever, and a bell crank lever having one arm connected to the pivot pin of the piston stem and another arm pivotally connected to the first mentioned link. 95

7. In a throttle valve operating mechanism, the combination of a throttle rod reciprocal in the direction of its length; a fluid pressure motor embodying two axially aligned spaced cylinders disposed in a plane perpendicular to the vertical plane of the throttle rod, and a piston element embodying two spaced pistons connected by a common stem, one of the pistons being disposed for reciprocation in each of the cylinders; a pivot pin connected to the piston stem; a slide block mounted on the pin; an auxiliary valve for controlling the application of fluid pressures to the pistons; a hand lever; and means

surfaces of the pistons, a hand lever, and means operatively connecting the hand lever, the throttle rod, the piston element, and the auxiliary valve, adapted to control the operation of the auxiliary valve in response to movements of the hand lever, and to translate reciprocal movements of the piston element to reciprocal movements of the throttle rod, said means including a link pivotally connected to the throttle rod and the hand lever, a control lever connected to the auxiliary valve, a link pivotally connected to the control lever and the hand lever, and a bell crank lever having one arm formed with a jaw slidably fitted on the block of the pivot pin of the piston stem, and another arm pivotally connected to the first mentioned link.

8. In a throttle valve operating mechanism, the combination of a throttle rod reciprocal in the direction of its length; a 130

fluid pressure motor embodying two axially aligned spaced cylinders disposed in a plane perpendicular to the vertical plane of the throttle rod, and a piston element embodying two spaced pistons connected by a common stem, one of the pistons being disposed for reciprocation in each of the cylinders; an auxiliary valve for controlling the application of fluid pressures to the pistons; 70 a hand lever; and means operatively connecting the hand lever, the throttle rod, the piston element, and the auxiliary valve, adapted to control the operation of the auxiliary valve in response to movements of the hand lever, to translate reciprocal movements of the piston element to reciprocal movements of the throttle rod, and in the emergency of failure of fluid pressure to operate the throttle rod in response to the application of 75 manual pressure to the hand lever, said means including a link pivotally connected to the throttle rod and the hand lever, a pair of spaced stops, a control lever connected to the auxiliary valve and disposed intermediate the stops, a link pivotally connected to the control lever and the hand lever, and a bell crank lever having one arm pivotally connected to the piston element and another arm pivotally connected to the first mentioned link.

9. In a locomotive the combination of a longitudinally reciprocable throttle valve rod; a fluid pressure motor cylinder; a piston in the cylinder reciprocable in a path substantially transverse to the reciprocations of the throttle rod; an auxiliary valve for controlling the operations of the piston; a hand lever pivoted to swing for operating the valve; a fixed element; and means operatively connected to the piston, to the valve rod, to the hand lever, and to the fixed element, for translating the reciprocal movements of the piston to reciprocal movements of the throttle valve rod and to insure simultaneous 40 45 swingings of the hand lever with reciprocations of the piston.

JAMES G. BLUNT.
ROGER W. CLIFFORD.
